SURGICAL FORCEPS OR CLAMP

Eagerton E. English, Denver, Colo.

Application January 25, 1950, Serial No. 140,499

3 Claims. (Cl. 128—321)

1

My present invention relates to surgical forceps or surgical clamps. It has to do particularly, although not exclusively, with improved forceps or an improved clamp which is so constructed and arranged as to prevent two-way slip when employed in connection with operations wherein it is necessary to engage and hold the broad ligament or other tissue in the female pelvis. It is, however, equally well adapted for use in performing other surgical operations wherein the prevention of two-way slip is essential.

Various surgical forceps and clamps have been made and particularly designed to prevent either side slip or end slip but as far as I am aware, there has never been a pair of forceps, or a surgical clamp available which was formed and proportioned as to combine in one instrument features which would prevent both side slip and end slip. Some instruments have appeared upon the market which were supposedly designed for the purpose of preventing two-way slippage but such instruments have failed in practice to function as intended. Over a long period of active practice, I have yet to find an instrument which meets, or even approaches, the usefulness and efficiency of that of my present invention.

It is, therefore, one of the important objects of my present invention to provide a new and improved pair of forceps, or an improved clamp, device, which is of relatively simple construction and which contains new and novel features whereby two-way slip in use is prevented.

Another object of the present invention is to provide a new and improved pair of forceps which combine in one instrument, means for preventing side slip and separate, although associated, means for preventing end slip.

A further object of the present invention is to provide an improved pair of surgical forceps or a surgical clamp wherein the clamping members or portions of the instrument are so shaped, arranged and proportioned as to cooperate one with the other to absolutely prevent two-way slip in use.

Another and important feature of the present invention is to provide new and improved forceps which in all respects resemble presently known surgical forceps but which combine new and novel means in a single instrument for prevent-

2

ing side slip and at the same time for preventing end slip.

A further object of the present invention is to provide an improved pair of forceps in which the pivotally connected crossed members are curved or bowed in their length to give access to places which were inaccessible to instruments having conventional straight or uncurved members.

A further and other important object of the present invention is to provide an improved pair of surgical forceps designed especially for use in grasping the broad ligament in the female pelvis, in which there is absolutely no danger of either side slip or end slip occurring during their use.

The foregoing and other objects of the present invention will appear from the following description and appended claims when considered in connection with the accompanying drawing forming a part of this specification wherein like reference characters designate corresponding parts in the several views.

In said drawing:

Fig. 1 is a fragmentary top plan view of one form of surgical forceps or clamp embodying the present invention, in open condition.

Figs. 2 and 3 are fragmentary perspective views, somewhat enlarged, of the cooperable and normally pivotally connected together and crossed ligament-engaging members or portions of the forceps of Fig. 1.

Fig. 4 is an enlarged fragmentary perspective sectional view of a portion of one of the ligament-engaging or gripping members of the forceps, illustrating one embodiment of the means for preventing side slip.

Fig. 5 is a vertical sectional view through the cooperable ligament-engaging or gripping portions of the forceps, shown substantially in closed position.

Fig. 6 is an end elevational view looking toward the closed outer ends of the gripping portions or members of the forceps of the preceding views; and

Figs. 7 and 8 are similar and somewhat enlarged fragmentary perspective views of the outer end portions, tips, or terminals of the ligament-gripping members of the forceps, illustrating in detail one embodiment of the means for preventing side slip and also the stop means for preventing end slip.

Before explaining in detail the present invention it is to be understood that the invention is not limited in its application to the details of construction and arrangement of parts illustrated in the accompanying drawing, since the invention is capable of other embodiments and of being practiced or carried out in various ways. It is to be understood also that the phraseology or terminology employed herein is for the purpose of description and not of limitation, and it is not intended to limit the invention claimed herein beyond the requirements of the prior art.

Referring now particularly to the drawing, the improved surgical forceps or clamp of the present invention is generally of scissors-like formation, comprising a pair of elongated crossed members 10 and 11 which are pivotally connected together intermediate their ends in conventional manner by means of a pivot pin, or the like, 12. Member 10 is typical of the two crossed members and comprises at one side of pivot 12, a shank and a handle portion terminating in a finger or thumb-receiving loop or eye 13 and an inwardly or laterally projecting preferably ribbed or corrugated portion 14 which is adapted to cooperate with a similar portion (not shown) on member 11, to hold the members 10 and 11 closed together when desired. That portion of member 10 at the opposite side of pivot 12 is the ligament-gripping or engaging portion, represented as a whole at 15. The outer end or tip 16 of portion 15, as shown, terminates in the male or V-shaped single projection 17 of a rat tooth-like structure or formation.

The other one of the crossed members 11 has at one side of pivot 12, a shank which terminates in a handle portion corresponding generally to the portions 13 and 14 of member 10, there preferably being duplicated a ring, eye, or the like member (not shown) but similar to eye 13 and a laterally projecting member, similar to member 14. This latter member (not shown) is intended to cooperate with the so-called friction member 14 to hold the forceps in closed position.

That portion of elongated member 11 which is located at the opposite side of pivot 12 is the gripping portion of said member and is represented as a whole at 18. The outer end of portion 18 preferably terminates in a two-part or two-piece female member or socket 19 of a rat tooth-like structure or formation, as best seen in Figs. 3, 6 and 7, and comprising, as shown, two similarly shaped spaced members providing therebetween a substantially V-shaped groove or socket to receive the male rat tooth-member 17 when the parts are closed together, as in Fig. 6.

With particular reference to Figs. 3, 4, 5, and 7, the ligament-gripping or engaging member or portion 18 is preferably provided on its inner face or surface with a series of corrugations, shown as a whole at 20, which extend longitudinally of member 18 and which provide a series of substantially parallel alternating upstanding preferably rounded ribs or projections 21 and similarly shaped grooves or recesses 22, see particularly Fig. 4.

As clearly seen in Fig. 1, member 18 is curved or bowed longitudinally. It will also be seen in this figure that companion and cooperating gripping member or portion 15 is also curved or outwardly bowed in its length.

With particular reference to Figs. 3 and 7, it will be seen that the female members or portions 19 of the rat tooth-like formation are dis-

posed at the outer ends of the corrugations 20 and provide, in effect, upstanding or inwardly directed stop members defining the outer ends of said corrugations.

Referring now particularly to Figs. 2, 5 and 8 it will be seen that gripping member or portion 15 of member 10 is similarly provided with a series of corrugations, shown as a whole at 23. These corrugations also extend longitudinally of portion 15 and comprise a series of longitudinally extending projecting members or ribs 24 with intervening longitudinal valleys or grooves 25. Each of the ribs or projecting portions 24 is disposed opposite a groove or recess 22 in member 18 and each recess or depressed portion 25 is likewise disposed opposite a projection or rib 21 formed on member 18. Thus, when the members 15 and 18 are moved together the corresponding alternate longitudinal ribs and grooves of the two members will, upon closing pressure being applied to the handle portions of the forceps, interfit and cooperate to grasp the broad ligament, for example, to prevent any possibility of side slip, while at the same time the cooperating male and female members 17 and 19 of the rat tooth-like formation located at the ends of portions 15 and 18, respectively, and defining the outer ends of the grooves and recesses as mentioned above, cooperate to provide stop means which positively prevent end slip with respect to the broad ligament, or the like, being gripped or engaged by the forceps.

As mentioned above, the entire members 10 and 11 of the forceps or surgical clamp, or at least the gripping portions 15 and 18, respectively, thereof, are preferably curved or bowed outwardly in opposite directions in their length. Where the members 10 and 11 are bowed throughout their length, the forceps herein give access to places not readily reached and which were virtually inaccessible with previously known and procurable surgical forceps. Moreover, the curvature or outward bowed condition of members or portions 15 and 18 permit a firmer gripping action upon the part engaged by them.

The degree of curvature of the members 10 and 11, or of only the portions 15 and 18 thereof, may vary in accordance with the particular job which is to be done by the forceps.

I claim:

1. Surgical forceps comprising a pair of elongated crossed members pivotally connected together for scissors-like movement, said members each having a handle portion disposed at one end and on one side of the pivotal connection and a gripping portion disposed at the opposite side of said connection, said gripping portions being bowed outwardly with relation to each other and having cooperable interfitting longitudinal corrugations formed on their opposed inner surfaces and extending substantially throughout the length of said surfaces, and a rat tooth-like formation provided on the outer free ends of the gripping portions beyond said longitudinal corrugations.

2. Surgical forceps according to claim 1, wherein the outwardly bowed gripping portions of the elongated crossed members are in converging relationship to each other, and wherein the handle portions are bowed in diverging relationship to each other, whereby to provide a spring-like action of the cross members when the gripping portions thereof are brought together in ligament-engaging position.

3. Surgical forceps comprising a pair of elongated

gated crossed members pivotally connected together for scissors-like movement, said members each having a handle portion disposed at one end and on one side of the pivotal connection and a gripping portion disposed at the opposite side of said connection, said gripping portions having cooperable interfitting longitudinal corrugations formed on their opposed inner surfaces, and inwardly directed interfitting male and female members formed on the outer free ends of the gripping portions beyond but adjacent the longitudinally corrugated inner surfaces, said elongated crossed members being gradually curved outwardly in opposite directions substantially

throughout the length thereof whereby to provide a spring-like action in the gripping portions when the forceps are in use.
